TABLE HOCKEY GAME BOARD

Bernard J. Tuschak and William R. Felege, Girard, Pa., and Harvey Lepselter, Bayside, N.Y., assignors to Louis Marx & Co., Inc., New York, N.Y.

Filed June 8, 1972, Ser. No. 261,140

Term of patent 14 years

Int. Cl. D21—01

U.S. Cl. D34—5 SS

FIG. 1 is a side perspective view of a table hockey game board embodying our new design;

FIG. 2 is a side elevational view thereof;

FIG. 3 is a top plan view thereof; and

FIG. 4 is an end view thereof, both ends being the same.

We claim:
The ornamental design for a table hockey game board, as shown and described.
